WORK CLAMP FOR USE ON A DRILL PRESS

Clarence A. Schumacher, Aurora, Colo.

Application May 24, 1956, Serial No. 587,137

3 Claims. (Cl. 77—63)

The present invention relates to certain new and useful improvements in a clamp which is expressly, but not necessarily, appropriately designed and constructed for use in securely positioning and holding work on a drill press table for drilling requirements.

In carrying out a preferred and therefore specific embodiment of the concept a practical and reliable clamp has been evolved and produced, one which facilitates placing, clamping and holding the work on the drill press table during the drilling stage and may be expediently and rapidly released so that when the drilling operation has been completed the clamp, usually employed in a group of clamps may be quickly detached and placed aside for the next operational step and so that the drilled work piece may be likewise removed from the press.

Stated along other and similar lines, the improved clamp has been designed with the idea in the mind of saving man hours and speeding up production in jig and drill press departments and any place where the use of clamps and clamping requirements are involved, for instance, in airplane factories and the like.

With a view toward achieving the desired end results with efficiency and looking toward satisfactory accomplishment and production of a highly desirable clamp, advantageous over C-clamps, a triple-part construction is employed. A principal part comprises an L-shaped body member the long limb of which is provided with a toothed rack on which slideable or relatively movable jaw means is shiftable, is provided with a pivoted grip, and a lever-operated cam arrangement for more satisfactorily applying and removing the grip. On the short arm there is complementary jaw means which, more specifically, functions as a sort of an anvil and is bound, when in use, against the underside of the drill press table.

Other objects, features and advantages will become more readily apparent from the following description and the accompanying sheet of illustrative, but not necessarily restrictive, drawings.

In the drawings, wherein like numerals are employed to designate like parts throughout the view:

Figure 1 is a fragmentary elevational view of a drill press showing a piece of work on the work table illustrating two of the specially devised improved work clamps and how they are preferably used;

Figure 2 is an edge elevation on a slightly enlarged scale of the improved clamp;

Figure 3 is a side view on approximately the same scale but with portions broken away to disclose the details and arrangement thereof;

Figure 4 is a section on the vertical line 4—4 of Figure 3; and

Figure 5 is a fragmentary detail view showing the cam construction in a position slightly different from that appearing in Figure 3.

Although the clamp was devised with the thought in mind that it is in effect a vise of a readily applicable and removable type for a drill press table, it will be evident

2

that the novelty resides structurally and functionally in the clamp regardless of its purpose and use. In Fig. 1, to assist in presenting the invention, the numeral 6 designates, generally speaking, a stand of a drill press wherein 5 the drill is denoted at 8 and the drill press table at 10. The work piece 12 is held partly in its intended drilling position by way of upstanding adjustable edge-engaging lugs or pins 14. Any number of these special clamps would be used to assist in firmly binding the work piece 10 on the table for drilling steps. Each clamp is the same and the description of one will suffice for all. To this end, and as seen in Fig. 3 the L-shaped body member is denoted as an entity by the numeral 16. It is a sturdy metal part comprising a long limb or arm 18 one edge 15 of which is formed with teeth to provide a rack 20. The short arm 20 carries the readily applicable and removable jaw unit 24 which is also herein described as an anvil. The anvil portion 26 is constructed so that it is bound firmly beneath the work table. There is a loop portion 28 which slides on the short arm and is held in place by a setscrew 30.

The novelly constructed shiftable jaw means is denoted by the numeral 32. This is characterized by a substantially U-shaped member having a bight portion 34 carrying a setscrew 36 engaging the edge 38 of the long arm 18. The arm portions 40 straddle and extend well beyond the toothed rack and bridging and rigidly secured to the upper edges of the intermediate portions of the arms there is a dog 42 engaging the rack teeth. Thus the dog and 30 setscrew make it possible to adjust this U-shaped member up and down to its primary or initially set position. The hingedly and pivotally mounted jaw or grip is denoted by the numeral 44 and this is provided with flanges 46 which straddle and are hingedly mounted as at 48 on an 35 ear 50 of the quick-adjusting actuator 52. This is confined for operation between the outer ends of the arms 40 and it is of elongate or ovate form and is hingedly mounted for limited swinging movement as at 54. This member 52 has a central substantially circular opening or 40 hole 56 therein which serves to accommodate a circular cam 58. An edge portion 60 of the hole, as best seen in Fig. 5, is offset to provide a stop shoulder so that the bodily travelled motion of the cam is limited when it comes against the shoulder, making it necessary to turn 45 the cam first in one direction and then in the other by way of the lever 62. The lever 62 has a crank portion 64 which extends eccentrically through and operates the cam in a generally obvious manner.

In using the clamping devices they are assembled on 50 the drill press table in the manner generally illustrated in Fig. 1. The drill press table is one which has a marginal flange or skirt and obviously the anvil member or jaw 24 is shifted and held by the setscrew so that the jaw means 32 above it will be in readiness to be adjusted toward and 55 from the work piece. The primary adjustment is made by way of the setscrew 36 and the U-shaped member 32 with its dog 42 engaging the rack teeth 20. The planned adjustment is made by operating the lever actuated cam and the pivoted block-like member 52 which carries the 60 self-leveling jaw face or grip 44.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

70 1. A clamp comprising a substantially L-shaped body member having long and short arms, said long arm being

provided with rack teeth, an anvil member slidably and operably mounted on said short arm and provided with adjustable retaining means engageable with the short arm permitting the anvil member to be positioned and retained where desired, a U-shaped member slidably mounted on the long arm with its arm portions straddling the long arm and provided with a fixed dog adjustably engageable with the rack teeth, the arms of said U-shaped member projecting well beyond said teeth, a block-like member operatively confined between said arms and pivotally mounted at one end between the arms, provided intermediate its ends with an opening, a jaw member pivotally connected to the other end of said block-like member, a cam confined for operation in the opening in said block-like member, a lever having a crank at one end, said crank extending through bearings provided therefor in the arms of said U-shaped member and being connected with said cam whereby the cam may be adjusted.

2. A work clamp for use on and in conjunction with a drill press comprising a substantially L-shaped body member having long and short arms, said long arm being provided along one longitudinal edge with finely graduated transverse rack teeth, the other edge being smooth, an anvil member having a loop portion slidably and operatively mounted on said short arm and provided with adjustable retaining means engageable with the edge of the short arm and permitting the anvil to be positioned and be retained wherever necessary or desired, the anvil proper projecting at right angles beyond said short arm and being disposed normally in spaced parallelism in relation to the rack teeth, a U-shaped slide having a bight portion and arm portions, said bight portion being opposed to the edge of the long arm opposite to the edge with the rack teeth and said bight portion having a setscrew engageable with the cooperating edge, said arms having free end portions straddling the long arm and projecting beyond the rack teeth and terminating for cooperative relationship with the anvil, a rigid dog bridging and rigidly secured to the upper edge portions of the intermediate portions of the arms, said dog being in plane above said upper edges and positioned for cooperation with the rack teeth so that the dog and setscrew make it possible to adjust the U-shaped slide and to hold it in its initially set position, a quick-adjusting actuator device confined and hingedly mounted between the outer end portions of said arms, a jaw cooperable with said dog and hingedly connected with a free swingable end portion of said actuator device, and crank-operated cam and slot means cooperating with the actuator device and said arm and serving to tighten and loosen

said jaw when cooperating with the workpiece interposed between the jaw and anvil.

3. A work clamp for use on and in conjunction with a drill press comprising a substantially L-shaped body member having long and short arms, said long arm being provided along one longitudinal edge with a finely graduated transverse rack teeth, the other edge being smooth, an anvil member having a loop portion slidably and operatively mounted on said short arm and provided with adjustable retaining means engageable with the edge of the short arm and permitting the anvil to be positioned and be retained wherever necessary or desired, the anvil proper projecting at right angles beyond said short arm and being disposed normally in spaced parallelism in relation to the rack teeth, a U-shaped slide having a bight portion and arms, said bight portion being opposed to the edge of the long arm opposite to the edge with the rack teeth and said bight portion having a setscrew engageable with the cooperating edge, said arms having free end portions straddling the long arm and projecting beyond the rack teeth and terminating for cooperative relationship with the anvil, a rigid dog bridging and rigidly secured to the upper edge portions of the intermediate portions of the arms, said dog being in plane above said upper edges and positioned for cooperation with the rack teeth so that the dog and setscrew make it possible to adjust the U-shaped slide and to hold it in its initially set position, a quick-adjusting actuator device confined and hingedly mounted between the outer end portions of said arms, a jaw cooperable with said dog and hingedly connected with a free swingable end portion of said actuator device, said actuator device being of elongated form, the central portion thereof being provided with a substantially circular hole, a cam confined for operation in said hole and located between the adjacent inner surfaces of said arms, said arms being provided with bearings, and a handle having a crank mounted for rotation in said bearings, said crank extending eccentrically through and being rigidly joined to said cam in a manner to rotate and thus operate the cam.
